Dec. 513

Benj: Wardwell of Fall River Mass & Ephraim R. Bartow of Providence R. I.
Letters Patent No 513 Dated Oct 19th 1852

The schedule referred to in these Letters Patent and making part of the same

To all Persons to whom these Presents shall come.

Be it known that we, Benjamin Wardwell (of Fall River of the County of Bristol and State of Massachusetts) and Ephraim R. Bartow of Providence in the County of Providence and State of Rhode Island have invented or produced a new ornamental design for a baking Range; and we do hereby declare that the same is represented in the following specification and the accompanying drawings.

Of the said drawings Figure 1 is a perspective front elevation of our said range. Figure 2 is a top view of the top plates over the boiling and baking chamber. Figure 3 is a horizontal section taken through the lower sets of doors. Figure 4 is a front view of one of the side plates. A. B of Figure 1. Figure 5 is a view of the side plates of the flue around the oven or that vertical plate on the left of the oven resting on the top plate C of the boiling chamber. Figure 6 is a horizontal section of the plate seen in Figure 5 the section being taken through the bands of the wheat sheaves. Figure 7 is a vertical section of such plate taken through the middle of one of the wheat sheaves.

Figure 8. is a vertical & middle section of the side plate seen in Figure 4. Figure 9 is a vertical section taken on the line from D to E₁ of Figure 1. Figure 10 is a vertical section taken on the line F to G of Figure 1.

The main design which we have produced is not to be understood to include the brickwork, boiling vessels or smoke discharge pipe as seen in Figures. It only has relation to the form or configuration of the ornamental plates fronting and on the sides of the oven, fireplace and a chamber under the oven.

The oven is supposed to be an elevated one and to have underneath it a chamber which has two doors H. I. in front of it. The oven doors are seen at K. L. while the fireplace doors are shown at N. O. P. Q.

The principle of the design on each of the larger fireplace doors and on the oven doors, and chamber doors consists of a wheat sheaf, surrounded by a running vine enclosed by a projecting moulding or beads or series of mouldings as seen in the drawings.

The ornamental character of each side plate A. B. or front plate R. S. consists of a truncated pyramidal, lozenge shaped projection from which spring in opposite directions two lance heads. In line of each of these lance heads there is another lance head in a reversed position, the whole being in a sunken panel and surrounded by a cordon of mouldings.

We claim the design consisting of the combination of the wheat sheaf, running vine, and enclosing fillet or bead as placed on each of the oven or fireplace or chamber doors.

And we also claim the ornamental design on either of the plates A. B. R. S. as described.

In testimony whereof we have hereto set our signatures
this sixteenth day of September A.D. 1852
